UNITED STATES PATENT OFFICE.

WILLIAM E. COOK, OF NEW YORK, N. Y., ASSIGNOR TO PEERLESS INSULATED WIRE AND CABLE COMPANY, OF NEW YORK, N. Y., A CORPORATION OF DELAWARE.

WIRE-COVERING MACHINE.

Application filed January 17, 1921. Serial No. 437,726.

To all whom it may concern:

Be it known that I, WILLIAM E. COOK, a subject of the King of the United Kingdom of Great Britain and Ireland, residing at St. 5 George, in the borough of Richmond, city of New York, county of Richmond, and State of New York, have invented certain new and useful Improvements in Wire-Covering Machines, of which the following is 10 a specification, reference being had therein to the accompanying drawings, which form a part thereof.

My invention relates to wire covering machines, and more particularly to a machine adapted to spirally wind cotton sliver or other similar absorptive, non-conductive material upon a conductor wire and spirally wind binding strands thereon to produce a 15 covered wire which thereafter is to be submerged in a bath of asphaltum or other electro non-conductive adhesive material to cause the saturation or impregnation of the covering of the wire therewith to weather-proof and impart additional insulating 20 properties thereto.

Heretofore, I have produced machines of this character adapted for use in automatically applying the covering sliver and binding strands. In such machines, however, 25 the structure was such as to apply one or more binding strands, all having the same pitch and extending parallel one with the other, affording capillary ducts between succeeding convolutions of the strands to facilitate saturation or impregnation of the 30 absorbent body of the insulation with the asphaltum or other composition.

Wires made in accordance with my aforesaid invention were so constructed as to permit the simultaneous unwinding of the strip 40 or web of sliver and binding strand, or required a variance in the pitch of the binding strands and of the strip or web of sliver or the winding of such strip or web and such strands in opposite directions to avoid 45 simultaneous unwinding of the sliver and the strands.

In a machine made in accordance with my present invention, the construction is such 50 that instead of a single binding strand or a set of binding strands, being applied to the body of sliver, a plurality of such strands or sets are successively applied thereto so as to cause one strand or set to 55 overlay the other, the overlaying strand be-

ing wound spirally in a direction the reverse of that of the underlaying strand, but not being interlaced or interwoven therewith in any way, and the succeeding convolutions of both strands or sets of strands being so 60 spaced apart and so imbedded in the body of sliver as to afford capillary ducts in the sliver between the relatively less absorptive strands.

The machine is so constructed that the 65 spirally wound sliver will be compacted immediately before the application of the underlaying binding strand or strands thereto, thus causing the subsequent expansion of the body of sliver in the portion thereof 70 unconfined by the strands to permit the extension of these portions of the sliver beyond the strand so that in the subsequent finishing operations, which, however, is not accomplished by a machine of my present 75 invention, the projecting portions and surface fibers will overlay the binding strands and thus secure a more permanent bond between the body of sliver and the binding strands.

The invention consists primarily in a machine embodying therein a rotatable platform adapted to receive one or more containers for a continuous strip or web of cotton sliver, a compacting die carried by and 80 rotatable with said platform, means adapted to continuously feed a wire axially of said platform and said die, a rotatable head mounted adjacent and beyond said compacting die in the direction of movement of the 85 wire, and having an axis of rotation concentric with the opening in said die, a spindle carried by said head and adapted to receive a spool of a binding strand, whereby said binding strand will be spirally wound upon 90 the spirally wound sliver while it is compacted, a second rotatable winding head axially aligned with said first named winding head and positioned beyond same in the direction of traverse of the wire, a spindle 95 carried thereby adapted to receive a spool of a binding strand, and means simultaneously rotating said winding heads in opposite directions, whereby the binding strand applied by said last named heads will 100 overlay and be wound in a direction opposite to the strand or strands applied by said first named head; and in such other novel features of construction and combination of 105 parts as are hereinafter set forth and de- 110

scribed, and more particularly pointed out in the claims appended hereto.

In the accompanying drawing, I have shown a vertical section of a machine embodying my invention.

In the embodiment of my invention shown in the drawings, I employ a rotatable platform *a* mounted upon a suitable bearing *b* carried by the base *c* of the machine. The platform *a* has an opening *a'* extending axially therethrough, which is aligned with an opening *b'* in the bearing *b*. Mounted within the base *c* is a tank *d* containing suitable guide rollers for a wire *e* to be covered, said tank being adapted to contain adhesive, and apply it to the surface of the wire to ensure a bond between the sliver which is shown at *f* and the conductor wire *e*, and facilitate the application of the sliver to the wire and ensure the desired permanency in relation of the wire and its insulating cover while in use.

Carried by the rotatable platform *a* is a can *g* for the sliver *f*, the platform *a* being adapted to receive one or more of such cans according to the desired thickness of insulation, which varies with wires of different uses.

The wire *e* is fed axially through the machine by means of the rollers *h*, which may be driven in any desired manner so as to impart substantially uniform continuous lineal traverse to said wire.

At *i* I have shown a rewind mechanism. Since the employment of feed rollers *h* and rewind reel *i* is old and well known in this art, I have not shown a detailed construction of such mechanisms in the drawing, but have illustrated them merely conventionally.

The sliver *f* is spirally wound upon the wire *e* as a result of the rotation of the platform *a* simultaneously with the lineal traverse of said wire, the pitch of the sliver being determined by the R. P. M. of the said platform as compared with the rate of traverse of the wire.

The sliver *f* is ordinary cotton sliver as delivered by a carding machine, the opposite edges of the sliver being folded upon the intermediate portion with one edge overlapping the other to secure a reduced thickness at the edges of the folded sliver, and give sufficient bulk to the strip or web to facilitate its application to the wire by reason of the added strength of the sliver and the added thickness thereof.

By reason of the loose matting of the fibers of the sliver, it is essential, after they have been applied to the wire, to compact it by means of a rotating reducing die, it being desirable under some conditions to subject the sliver to two or more compacting operations. In the form of the invention shown, I use two compacting dies *j* and *k*

arranged successively in the direction of movement of the wire *e*, the opening in one die being relatively smaller than that in the other. The dies *j* and *k* are supported by standards *m* carried by the platform *a*, so as to rotate therewith, and thus accomplish the compacting and close matting of the fibers, of the sliver, by a smoothing action which will avoid a tendency toward the separation of the overlapping edges of succeeding convolutions thereof.

Mounted adjacent the compacting die is a rotatable head *n* having a spindle or spindles *n'* thereon adapted to receive the spools *n²* containing a binding strand, thread or cord.

In practice it is customary to use a plurality of such strands in order to lay them in sets upon the compacted sliver, a condition arising from the comparative widths of the sliver and of the binding strand, the former ranging from an inch and a quarter to an inch and a half and the latter being an ordinary cotton, cord or thread. By using a plurality of such spindles the convolutions of the different strands of each set may be laid with a spacing of an eighth of an inch or more apart, thus affording capillary ducts therebetween, and still have the desired binding action upon the entire width of the sliver.

Beyond the head *n*, I provide a second rotatable head *o* carrying similar spindles *o'* upon which similar spools *o²* may be mounted, the heads *n* and *o* having openings for the passage of the covered wire axially aligned with the opening in the die *k*. Since the covered sliver will be held compacted by the binding strands from the spools *n²* after leaving the head *n*, no further compaction of the cover is required, and hence no compacting die is used adjacent the head *o*.

Each of the compacting heads is provided with tension devices *n³* and *o³* intermediate the spindles *n'* and *o'* respectively, and the opening through which the covered wire passes, so as to cause the binding strands from said spools to be imbedded in the sliver body of the covering.

I also provide the heads *n* and *o* with flanges *n⁴* and *o⁴* respectively, having guide openings therein adjacent the point of application of the binding strands to the covered wire to prevent entangling of the strands of the same sets and ensure the desired pitch in the application of the strands to the wire.

The platform *a* and the winding heads *n* and *o* may be driven in any desired manner or by means of any desired mechanism.

In the drawings I have shown the platform *a* as being driven by means of a bevelled gear *a²* carried by its hub, and meshing with the bevelled gear *p* deriving its power through the pulley *p'* upon the shaft *p²*.

Mounted upon the standard *q* is a shaft *r* parallel with the shaft *p*² carrying a bevelled gear *r'* in mesh with a bevelled gear *r*² upon the winding head *n*.

5 The shaft *r* is driven from the shaft *p*² by means of the pulleys *s* and *s'* and the belt *s*².

Also mounted upon the standard *q* is a shaft *t* parallel with the shafts *r* and *p*², carrying a bevelled gear *t'* meshing with the gear *t*² upon the head *o*.

The shaft *p*² is driven from the shaft *r* by means of the pulleys *u*—*u'* and the crossed belt *u*².

15 By the driving mechanism above described, the platform *a* and the binding heads *n* and *o* will be continuously rotated, the crossing of the belt *u*² causing the head *o* to rotate in a direction opposite to the direction of rotation of the head *n*, thus causing the strand from the spools *o*² to be wound with a spiral trend upon the covered wire in a direction opposite to that in which the strand from the spools *n*² is spirally 25 wound, the strand from the spools *o*² overlaying those from the spools *n*². By having the heads *n* and *o* turned at the same speed as the platform *a*, the pitch at which the binding strands are wound will be the same 30 as that at which the strip or web of sliver *f* is wound, although by the construction described, the rotary speed of the heads may be varied with relation to that of the platform or to each other to secure any desired 35 variance in the pitch at which the succeeding strands are wound.

If the speed of the head *n* is the same as that of the platform *a*, the same effect is secured as though the head *n* were rigidly secured to the die *k*. I prefer, however, to mount said head rotatably in relation to said die so that, if desired, the strand from the spools *n*² may be wound at a different pitch from that at which the sliver is wound.

45 The operation of the herein described machine is substantially as follows:—

In the operation of the machine, the wire *e* is threaded through the rollers in the tank *d*', the openings *b*' and *a*', the compacting 50 dies *j* and *k*, and the bearing for the head *o*. It is then passed over the feed rollers *h* to the rewind reel *i*.

The end of the sliver strip *f* from the can *g* is then applied to the adhesive coated wire, 55 or if a plurality of such strips or webs are to be applied, the ends of both of such are applied to the wire and the platform *a* is rotated under power derived from the driving mechanism.

60 As a result of such application of power, the wire *e* will be fed axially thereof through the machine and the sliver *f* will be spirally wound thereon at a pitch determined by the rate of lineal traverse of the wire as compared with the R. P. M. of the platform *a*.

As the covered wire passes through the die *j*, it will receive an initial compaction by the rotary movement of said die, thus reducing the diameter of the covering sliver and more closely matting the fibers thereof. 70 The die *k* will still further compact the covering sliver.

As the compacted sliver leaves the die *k*, the binding strands from the spools *n*² will be wound thereon, said strands being subjected to tension by the tension device *n*³, so that said strands will be imbedded in the surface of the sliver, the tendency of the sliver to expand substantially simultaneously with the application of said strands 80 causing the portions of said sliver not confined by said strands to bulge slightly as a result of such expansion. The strands from the spools *n*² will be wound in the same direction as the sliver *f* is wound, and may be 85 wound in the same or at a different pitch, as desired.

As the covered wire passes through the opening in the support for the winding head *o*, no compacting action occurs, the binding strand applied thereto by the head *n* making further compaction unnecessary and impracticable. As the covered wire passes the head *o*, the strands from the spools *o*² will be wound thereon in a direction the reverse. 90 of that in which the strands from the spools *n*² were wound, the tension upon said strands from the spools *o*² imbedding said strands in the expanded portion of said sliver intermediate the strands from the spools *n*², and 100 causing the strands last to be applied to overlay the other strands without being enmeshed in any way therewith, and in a manner to leave a multitude of closely adjacent capillary ducts through which the asphaltum 105 or other composition may readily penetrate to the entire body of the sliver.

In practice, I have found that the compressive action of the binding strands is limited to the portion of the sliver adjacent 110 the outer surface thereof, so that the asphaltum will pass readily to the body of the sliver between said strands and the wire *e*.

The unconfined portions of the sliver will project slightly beyond the binding 115 strands, and the surface fibers thereof will not be so closely matted but that, as a result of the immersion of the covered wire in the bath of asphaltum or other composition, and the subsequent waxing and finishing operations, the projecting portions of the sliver and said fibers will overlap the binding strands and thus anchor them firmly in position upon the sliver.

By the successive spiral windings forming the underlaying and overlaying strands above referred to, I not only secure a wire which, after subsequent saturation or impregnation with asphaltum or other composition, and finishing, will have a satis- 125 130

factory commercial finish, but one in which there will be no tendency of the sliver or of the confining strands to unwind after the cover has been applied to the wire and before or during its immersion in the bath, since the outer binding strand will check any tendency of the inner strand to unwind and the inner strand will relieve the outer strand from the stresses due to a tendency 10 of the sliver to expand before the matted fibers have been permanently set by the action of the asphaltum or other composition thereon.

It is not my intention to limit the invention 15 to the details of construction shown in the accompanying drawing, it being apparent that such may be varied without departing from the spirit and scope of the invention. I believe it to be broadly new 20 to provide a machine of the character described, with oppositely rotatable binding heads, for the purpose above referred to, and I intend to claim such broadly.

Having described the invention, what I 25 claim as new and desire to have protected by Letters Patent, is:—

1. A wire covering machine embodying therein a rotatable platform adapted to receive one or more containers for a continuous strip of cotton sliver, a compacting die carried by and rotatable with said platform, means adapted to continuously feed a wire axially of said platform and said die whereby as a result of the axial movement of said wire and the rotation of said platform, the sliver will be spirally wound upon the wire, a rotatable head mounted adjacent and beyond said compacting die in the direction of movement of the wire, 40 and having an axis of rotation concentric with the opening in said die, a spindle carried by said head and adapted to receive a spool of a binding strand, whereby said binding strand will be spirally wound upon the spirally wound sliver while it is compacted, a second rotatable winding head axially alined with said first named winding head and positioned beyond same in the direction of traverse of the wire, a spindle 45 carried thereby adapted to receive a spool of a binding strand, and means simultaneously rotating said winding heads in opposite directions, whereby the binding strand applied by said last named head will overlay and be wound in a direction opposite to the strand or strands applied by said first named head.

2. A wire covering machine embodying therein a rotatable platform adapted to receive one or more containers for a continuous strip of cotton sliver, a compacting die carried by and rotatable with said platform, means adapted to continuously feed a wire axially of said platform and said die whereby as a result of the axial

movement of said wire and the rotation of said platform, the sliver will be spirally wound upon the wire, a rotatable head mounted adjacent and beyond said compacting die in the direction of movement of the wire, and having an axis of rotation concentric with the opening in said die, a spindle carried by said head and adapted to receive a spool of a binding strand, whereby said binding strand will be spirally wound upon the spirally wound sliver while it is compacted, tensioning means operative upon the binding strand, a second rotatable winding head axially alined with said first named winding head and positioned beyond same in the direction of traverse of the wire, a spindle carried thereby adapted to receive a spool of a binding strand, tensioning means operative upon the binding strand, and means simultaneously rotating said winding heads in opposite directions, whereby the binding strand applied by said last named head will overlay and be wound in a direction opposite to the strand or strands applied by said first named head.

3. A wire covering machine embodying therein a rotatable platform adapted to receive one or more containers for a continuous strip of cotton sliver, means whereby an adhesive is applied to a conductor wire prior to its passage axially of said platform, a compacting die carried by and rotatable with said platform, means adapted to continuously feed a wire axially of said platform and said die whereby as a result of the axial movement of said wire and the rotation of said platform, the sliver will be spirally wound upon the wire, a rotatable head mounted adjacent and beyond said compacting die in the direction of movement of the wire, and having an axis of rotation concentric with the opening in said die, a spindle carried by said head and adapted to receive a spool of a binding strand, whereby said binding strand will be spirally wound upon the spirally wound sliver while it is compacted, tensioning means operative upon the binding strand, a second rotatable winding head axially alined with said first named winding head and positioned beyond same in the direction of traverse of the wire, a spindle carried thereby adapted to receive a spool of a binding strand, tensioning means operative upon the binding strand, and means simultaneously rotating said winding heads in opposite directions, whereby the binding strand applied by said last named head will overlay and be wound in a direction opposite to the strand or strands applied by said first named head.

4. A wire covering machine embodying therein a rotatable platform adapted to receive one or more containers for a continu-

ous strip of cotton sliver, two compacting dies arranged successively in the direction of movement of the wire, said dies having openings of progressively smaller dimensions and both being rotated in synchronism with said platform, means adapted to continuously feed a wire axially of said platform and said die whereby as a result of the axial movement of said wire and the 10 rotation of said platform, the sliver will be spirally wound upon the wire, a rotatable head mounted adjacent and beyond said compacting die in the direction of movement of the wire, and having an axis of 15 rotation concentric with the opening in said die, a spindle carried by said head and adapted to receive a spool of a binding strand, whereby said binding strand will be spirally wound upon the spirally wound 20 sliver while it is compacted, a second rotatable winding head axially alined with said first named winding head and positioned beyond same in the direction of traverse of the wire, a spindle carried thereby adapted 25 to receive a spool of a binding strand, and means simultaneously rotating said winding heads in opposite directions, whereby the binding strand applied by said last named head will overlay and be wound in 30 a direction opposite to the strand or strands applied by said first named head.

5. A wire covering machine embodying therein a rotatable platform adapted to receive one or more containers for a continuous strip of cotton sliver, a compacting die carried by and rotatable with said platform, means adapted to continuously feed a wire axially of said platform and said die whereby as a result of the axial movement of said 35 wire and the rotation of said platform, the sliver will be spirally wound upon the wire, a rotatable head mounted adjacent and beyond said compacting die in the direction of movement of the wire, and having an 40 axis of rotation concentric with the opening in said die, a spindle carried by said head and adapted to receive a spool of a binding strand, whereby said binding strand will be spirally wound upon the spirally wound 45 sliver while it is compacted, a second rotatable winding head axially alined with said first named winding head and positioned beyond same in the direction of traverse of the wire, a spindle carried by said head and adapted to receive a spool of a binding strand, and means simultaneously rotating said winding heads in opposite directions, whereby the binding strand applied by said last 50 named head will overlay and be wound in a direction opposite to the strand or strands applied by said first named head.

to rotate independently of the other, and means simultaneously rotating said winding heads in opposite directions, whereby the binding strand applied by said last 60 named head will overlay and be wound in a direction opposite to the strand or strands applied by said first named head.

6. A wire covering machine embodying therein a rotatable platform adapted to receive one or more containers for a continuous strip of cotton sliver, a compacting die carried by and rotatable with said platform, means adapted to continuously feed a wire axially of the platform and said die 65 whereby as a result of the axial movement of said wire and the rotation of said platform, the sliver will be spirally wound upon the wire, a head rotatably mounted beyond and closely adjacent said compacting die 70 in the direction of movement of the wire and having an axis of rotation concentric with the opening in the die, a spindle carried by said head and adapted to receive a spool of a binding strand, whereby said 75 binding strand will be spirally wound upon the spirally wound sliver while it is compacted, a support having a guide opening therethrough axially alined with the opening in said die, a second winding head rotatably 80 mounted upon said support, and positioned beyond same in the direction of traverse of the wire, a spindle carried by said head and adapted to receive a spool of a binding strand, whereby said 85 binding strand will be spirally wound upon the spirally wound sliver while it is compacted, a second rotatable winding head axially alined with the opening in said die, a second winding head rotatably 90 mounted upon said support, and positioned beyond same in the direction of traverse of the wire, a spindle carried by said head and adapted to receive a spool of a binding strand, whereby said 95 binding strand will be spirally wound upon the spirally wound sliver while it is compacted, a second rotatable winding head axially alined with said first named winding head and positioned beyond same in the direction of traverse of the wire, a spindle carried thereby adapted to receive a spool of a binding strand, and means simultaneously rotating said winding heads in opposite directions, whereby the binding strand applied by said last 100 named head will overlay and be wound in a direction opposite to the strand or strands applied by said first named head.

In witness whereof I have hereunto affixed my signature in the presence of two 105 subscribing witnesses, this 27th day of December, 1920.

WILLIAM E. COOK.
